Primary Examiner — Marianne N Pandozzi*Assistant Examiner* — Jae Liang(74) *Attorney, Agent, or Firm* — Head, Johnson, Kachigian & Wilkinson, PC(57) **CLAIM**

The ornamental design for an insulated glass, as shown and described.

DESCRIPTION

FIG. 1 is a perspective view of an insulated glass showing my new design;

FIG. 2 is a top view thereof;

FIG. 3 is a bottom view thereof; and,

FIG. 4 is a front view thereof, where the back, right side, and left side views are identical to the front view.
